United States Patent Office

Des. 178,591
Patented Aug. 28, 1956

178,591

GUN TURRET

Irwin R. Barr and Walter R. Roehmer, Kingsville, Md.,
assignors to Aircraft Armaments, Inc., Baltimore, Md.,
a corporation of Maryland

Application May 29, 1953, Serial No. 25,254

Term of patent 14 years

(Cl. D30—1)

FIG. 1

FIG. 2

Des. 178,591

Figure 1 is a side elevational view of a gun turret showing our new design;

We claim:

The ornamental design for a gun turret, as shown.
